UNITED STATES PATENT OFFICE

149,994

DESIGN FOR AN AIRPLANE

Dean E. Zongker, Wichita, Kans.

Application May 3, 1947, Serial No. 138,797

Term of patent 7 years

(Cl. D71—1)

To all whom it may concern:

Be it known that I, Dean E. Zongker, a citizen of the United States and a resident of Wichita, in the county of Sedgwick and the State of Kansas, have invented a certain new, original, and ornamental Design for an Airplane, described and claimed in the following specification and shown in the accompanying drawings, wherein:

Fig. 1 is a plan view of an airplane embodying the new design;

Fig. 2 is a side elevation thereof with the landing gear retracted;

Fig. 3 is a front elevation thereof with the landing gear retracted; and

Fig. 4 is a three-quarter front perspective view with the landing gear retracted.

What I claim is:

The ornamental design for an airplane, substantially as shown.

DEAN E. ZONGKER.
